UNITED STATES PATENT OFFICE.

STEVEN GRACEK, OF ELIZABETH, PENNSYLVANIA.

HORSESHOE.

1,113,117.

Specification of Letters Patent.

Patented Oct. 6, 1914.

Application filed October 15, 1913. Serial No. 795,191.

To all whom it may concern:

Be it known that I, STEVEN GRACEK, a citizen of the United States, residing at Elizabeth, in the county of Allegheny and State of Pennsylvania, have invented a certain new and useful Improvement in Horseshoes, of which improvement the following is a specification.

My invention relates to the class of horse 10 shoes having detachable toe pieces.

My invention has for its object to provide a simple and practical toe piece for shoes that can be readily applied and detached and means to automatically lock the 15 same to the shoe when applied thereto.

With the above objects in view, the invention consists in certain features of construction, in certain parts and combination of parts as hereinafter described in this specification and pointed out in the appended 20 claims thereof.

In the accompanying drawings forming a part of this specification, like detail parts in the several views are indicated by like 25 numerals and referred to by such in the specification, the various views illustrated in said drawings being as follows:

Figure 1 is an inverted plan of a shoe having my improvement applied thereto. Fig. 30 2 is a sectional side elevation thereof, on the line X—X of Fig. 1. Fig. 3 is an inverted plan of the front portion of the shoe, having the toe piece detached. Fig. 4 is a side elevation, in section on the line V—V 35 of Fig. 3. Fig. 5 is a front elevation of the toe piece. Fig. 6 is a transverse section through said toe piece.

As shown in said drawings, the shoe 1 having suitable calks 2 thereon is provided 40 in front with the two like openings 3 and 3 and the intermediate opening 4, said opening 4 being threaded. Fitted into said opening 4 is a screw plug or locking pin 5, capable of being adjusted vertically and 45 rotatively, the extended portion thereof being divided to form twin prongs 5' and 5', which before the toe piece is applied to the shoe remain in parallel relation, as shown in Fig. 4.

50 The toe piece 6, which may have a blunt or a sharpened tread edge, is provided with spaced pins 7 and 7, adapted to neatly fit the openings 3 and 3 of the shoe, and is fur-

ther provided with openings 8 and 8 inclining in opposite directions from the point 9, 55 intermediate of said pins, and adapted to receive the prongs of the locking pin.

In applying the toe piece, the same is positioned over the front portion of the shoe, with the point 9 thereof engaging between the ends of the prongs 5' and 5' of the locking pin, and driven into place, causing the pins 7 and 7 to enter the openings 3 and 3 and the prongs of the locking pin to be spread apart and enter the openings 60 8 and 8, projecting slightly through said openings, as shown in Figs. 1 and 2, the spreading of the prongs in said openings 65 effectually locking the toe piece to the shoe, the projecting ends of the pin prongs becoming 70 battered down, somewhat like that of riveting, during service, thus more effectually securing the toe piece to the shoe.

Should the prongs of the pin, when applying the toe piece to the shoe, not properly register with the inclined openings a slight turn of the pin will remedy the difficulty. Again, the pin may be adjusted vertically, by turning, before applying the toe piece so as to increase or decrease the length of the prongs 75 80 to pass in and through the openings in the toe piece.

When the toe piece becomes so worn from usage as to be unfit for further service, the worn one may be readily removed from the 85 shoe by prying the same therefrom by means of a suitable instrument, during which operation the prongs on the locking pin become straightened out and, in many instances, may be again of service to lock the 90 new toe piece to the shoe.

Having shown and described my invention, I claim:

1. The combination with a horse shoe having a removable toe piece fitted thereto 95 by pins, said toe piece having oppositely inclined openings formed therethrough intermediate said pins, of a locking pin removably secured to the shoe and provided with prongs extending through said inclined 100 openings of the toe piece.

2. The combination with a horse shoe having a removable toe piece fitted thereto by pins, said shoe having a threaded opening formed therein intermediate the pins of the 105 toe piece and said toe piece having oppo-

sitely inclined openings therein extending to the threaded opening in the shoe, of a locking pin threadably secured in said shoe opening and having prongs formed thereon which extend through the inclined openings of the toe piece.

In testimony whereof, I have hereunto

signed my name in the presence of two subscribing witnesses.

STEVEN GRACEK
